UNITED STATES PATENT OFFICE

107,324

DESIGN FOR A GRAVE VAULT

Norman J. Schnelker, Galion, Ohio, assignor to Central Ohio Steel Products Co., Galion, Ohio, a corporation of Ohio

Application October 13, 1937, Serial No. 72,150

Term of patent 7 years

To all whom it may concern:

Be it known that I, Norman J. Schnelker, a citizen of the United States, residing at Galion, in the county of Crawford and State of Ohio, have invented a new, original, and ornamental Design for a Grave Vault, of which the following is a specification, reference being had to the accompanying drawing, forming part thereof.

The figure is a perspective view of a grave vault embodying my new design.

I claim:

The ornamental design for a grave vault, as shown.

NORMAN J. SCHNELKER.
